US00D567279S

(12) **United States Design Patent** (10) **Patent No.:** **US D567,279 S**
Chisom et al. (45) **Date of Patent:** **** Apr. 22, 2008**

(54) **EYEWEAR RETAINER**

(75) Inventors: **Beirne Chisom**, Salt Lake City, UT (US); **John Bishop**, Sandy, UT (US); **Lee Scott**, Meridian, ID (US)

(73) Assignee: **Chums, Inc.**, Salt Lake City, UT (US)

(**) Term: **14 Years**

(21) Appl. No.: **29/280,376**

(22) Filed: **May 24, 2007**

(51) **LOC (8) Cl.** **16-06**

(52) **U.S. Cl.** **D16/339**

(58) **Field of Classification Search** **D16/123, D16/126, 128, 311, 309, 312, 330, 335, 336, D16/339; D11/1-11, 44, 48, 49, 50, 53, D11/69, 71, 75, 79, 80, 81, 82, 85, 86, 97, D11/99, 100; 428/50, 100, 15, 16, 79; D12/199; 40/299; D20/10, 11; 351/41, 43, 51, 52, 351/66, 156, 157, 158; 63/1.1, 2; D3/207, D3/208, 209, 210, 211; D2/866; 24/3.3; D8/38**
